UNITED STATES PATENT OFFICE.

RALPH D. MERSHON, OF NEW YORK, N. Y., ASSIGNOR TO WESTINGHOUSE ELECTRIC & MANUFACTURING COMPANY, A CORPORATION OF PENNSYLVANIA.

MEANS FOR EXTINGUISHING FIRES IN OIL-FILLED RECEPTACLES.

No. 853,253.

Specification of Letters Patent.

Patented May 14, 1907.

Application filed February 20, 1904. Serial No. 194,464.

To all whom it may concern:

Be it known that I, RALPH D. MERSHON, a citizen of the United States, and a resident of New York, county of New York, State of New York, have invented certain new and useful Improvements in Means for Extinguishing Fires in Oil-Filled Receptacles, of which the following is a specification.

As is well known, certain receptacles permanently filled with oil are very liable to injury or destruction from the ignition of the oil. This is particularly true in the case of devices of the class known as "oil-cooled" electrical apparatus, including transformers, induction coils, condensers, &c., in which the heat developed by the resistance of the conductors to the passage of the electric current or by short circuits sometimes results in the ignition of the oil. Fires of this character for reasons well known are difficult to cope with, and although various plans have been proposed for extinguishing them I am not aware that any of such plans have been found to be practicable. These considerations have led me to devise means by which such fires may be extinguished quickly and easily and which may be operated without serious injury to or destruction of the apparatus.

My improved means will be more readily understood by reference to the accompanying drawing, in which—

1 represents the casing of an oil-filled receptacle—*e. g.*, a transformer or other electrical device. This casing is made substantially liquid-tight to contain a body of oil 2, which in the case supposed is designed either to insulate or to cool the transformer-coil 3. The upper part of the case has connected to it in any convenient manner a comparatively small pipe 4, extending some distance away, while to another part of the casing, and preferably at or near the bottom of the same, is connected a second pipe 5 of suitable size, having a valve 6, by means of which the flow of liquid through it may be readily controlled. Through this pipe 5 a liquid is to be admitted to the tank in order

to displace and expel the oil, and for this purpose I may employ any liquid which is heavier than the oil in the tank and which is preferably of a non-inflammable nature and capable of extinguishing fire. For this purpose ordinary water may be employed, in which case the pipe 6 is connected to any suitable source of water-supply, preferably under considerable pressure. If for any reason the oil in the receptacle should take fire or is in danger of ignition, the valve 6 is opened and water admitted into the casing. Since the water is heavier than the oil, the latter will be rapidly displaced and expelled from the casing through the pipe 4, leaving the casing filled with water. At the same time fire in any combustible material which may have been used in the construction of the apparatus will be extinguished by the direct application of the water, which thus performs a useful function in addition to that of expelling the oil.

It will of course be understood that these means may be employed with any apparatus containing oil, and I am therefore not limited to its use with electrical transformers, as illustrated.

I claim as my invention:

The combination with an oil containing receptacle, and an electrical apparatus submerged in the oil and subject under the conditions of its operation to the danger of igniting the oil, of a free outlet for the oil above the normal height thereof, a discharge pipe extending from said outlet to a point beyond the limit of exposure to fire, a water inlet pipe connected with the lower end of the receptacle, and means whereby water from the inlet pipe may be caused to replace the oil and cause its discharge through the said discharge pipe.

Signed at New York, in the county of New York, and State of New York, this 15th day of February, A. D. 1904.

RALPH D. MERSHON.
